DESIGN FOR A JAR

Norman F. Steuer, San Francisco, Calif., assignor to Owens-Illinois Pacific Coast Company, San Francisco, Calif., a corporation of Delaware

Application September 22, 1937, Serial No. 71,724

Term of patent 14 years

To all whom it may concern:

Be it known that I, Norman F. Steuer, a citizen of the United States, residing at San Francisco, in the county of San Francisco and State of California, have invented a new, original, and ornamental Design for a Jar, of which the following is a specification, reference being had to the accompanying drawing, forming a part thereof.

In the drawing:

Fig. 1 is a side elevational view of a jar showing my new design, that area of the surface ornamentation lying between the horizontal dot and dash lines being representative of the details of the remaining surface decoration shown on one face of the jar.

Fig. 2 is an end elevational view thereof.

Fig. 3 is a sectional view thereof taken substantially along the line 3—3 of Fig. 1.

I claim:

The ornamental design for a jar, substantially as shown and described.

NORMAN F. STEUER.
